UNITED STATES PATENT OFFICE.

JOSEPH F. STACKHOUSE, OF COLWYN, PENNSYLVANIA.

SHUTTER-OPERATOR.

SPECIFICATION forming part of Letters Patent No. 716,126, dated December 16, 1902.

Application filed March 7, 1902. Serial No. 97,097. (No model.)

To all whom it may concern:

Be it known that I, JOSEPH F. STACKHOUSE, a citizen of the United States, and a resident of Colwyn, State of Pennsylvania, have invented certain Improvements in Devices for Operating Shutters, of which the following is a specification.

My invention relates to certain improvements in devices for operating window-shutters from the inside of the building to which they are attached.

The object of my invention is to provide an improved device for opening and closing window-shutters from the inside of the building which may be operated without raising the sash of the window and which in addition to its other functions is capable of retaining or locking the shutter in any desired position.

A further object is to provide an improved device which while being of a simple and inexpensive construction shall at the same time be reliable in action and not likely to get out of order.

These objects I attain as hereinafter set forth, reference being had to the accompanying drawings, in which—

Figure 1 is a sectional plan view showing my improved device applied to a pair of ordinary window-shutters, one of said shutters being in an open and one in a closed position. Fig. 2 is an elevation of the lower portion of the inside of the window-frame illustrated in Fig. 1. Fig. 3 is a front elevation of the device set in the square and bead of the window-sill for holding the shutter-operating rods in a fixed position. Fig. 4 is a sectional plan view taken through the window-sash and the square and bead of the sill, showing the detail construction of the device illustrated in Fig. 3; and Fig. 5 is an elevation of the piece for preventing motion of the shutter-operating rods when these are in position to hold the shutter open.

In the above drawings, A is a window-frame of the ordinary construction in which is a sash B, having hinged to it the shutters C. Each of these shutters is provided with a small casting or bracket c, to which is pivoted one end of a rod c', there being also fastened to the shutter a fulcrum-piece c⁴, against which the rod c' bears when said shutter is

in its open position. To the other end of this rod is similarly pivoted a second and somewhat longer rod c², which passes over the top surface of the window-sill b, under the sash B, which is recessed, as shown at b' in Fig. 4, to accommodate it. The said rod then passes through the upwardly-projecting portion of the window-sill b², technically known as the "square" and "bead," and is provided at its inner end with a head c³.

Instead of allowing the rod c² to pass through an ordinary slot in the part b² of the sill I cut away a portion of this latter and fit therein a casting or fixture D of the form shown in Figs. 3 and 4. As illustrated, this fixture is rectangular in outline and of the same height as the combined height of the square and bead b² of the sill, having within it a cavity for the accommodation of a cylindrical piece d. There is through this latter an opening d' for the passage of the rods c' and c². The piece d is free to turn within this cavity, and I preferably provide an inclined set-screw d², passing through a threaded hole in the top of the fixture D, which may, if desired, be screwed down, so as to engage one of the rods within the said cylindrical piece d to prevent it, with the attached shutter, from moving. A piece e, fastened to the window-sill outside of the sash, is made with a depression or recess e' in its upper surface for the reception of the rod c² when this latter has been moved into a position corresponding to the wide-open position of the shutter. A second bracket or casting e² is fastened to the window-sill, as shown in Fig. 1, this being on the inside and also having a depression in its upper surface for the reception of the rod c² when the shutter has been moved into its closed position.

When it is desired to close the shutter, the set-screw d², which is preferably maintained in a position to prevent motion of the rods and shutter, is unscrewed and the head and inner end of the rod c² are pressed downwardly, raising the said rod out of the slot or depression e' in the piece e in which it rested while the shutter was open. The inner end of the rod is then pressed toward the adjacent side of the window-frame and at the same time pulled inwardly, thus swinging

the shutter on its hinges and causing the bars to move inwardly through the cylindrical pivotal piece d in the fixture D. After the shutter has been swung on its hinges to a closed position, as shown on the left-hand portion of Fig. 1, and the joint between the rods or bars c' and c^2 has passed through the piece D the rod c^2 is turned so that it may be placed in the notch in the piece e^2 , as shown in Figs. 1 and 2.

In order that it may be impossible to open the shutter from without, the set-screw d^2 is set down tightly upon the rod c' when it passes through the pivoted piece d , there being an opening through the top of said piece, so as to allow the screw to directly engage with a notch in said rod c' , and thereby prevent its movement. If it is desired to open the shutter, the set-screw d^2 is slackened off, and after the rod c^2 has been moved from the notch in the piece e^2 the rods c' and c^2 are pushed through the piece d of the fixture D, the inner end of the latter of these rods being pushed away from the adjacent side of the window-frame, so as to cause the shutter to open to its fullest extent. Just before the shutter has attained this open position the inner end of the rod c^2 is pressed downwardly, thus causing it to move over the piece e and finally allowing it to enter the slot e' therein, when the shutter has come to its full-open position, as above indicated.

It will be noted that my improved device can be applied to shutters with but very little modification or cutting of either window sash or frame and that it requires but very little labor for its application to existing structures. By means of the improved fixture D, which is set in the square and bead projecting upwardly from the inner portion of the window-sill for the passage of the shutter-operating rods, I avoid having any objectionable or unsightly openings through which water or air could enter. It will be further noted that my device is of the utmost simplicity, having no parts liable to get out of order, and, moreover, is of a relatively inexpensive construction.

It is to be noted that one of the most important applications of my improved shutter-operating device is to buildings provided with fire-shutters. In an emergency such shutters can be positively and quickly swung on their hinges to their closed position without the danger and loss of time usually incurred by the necessity of raising the window-sash.

I claim as my invention—

1. The combination in a device for operating a window-shutter, of a plurality of rods pivoted together and pivotally connected to the shutter, a revoluble piece set in the square and bead of the window-sill having an opening through which said rods are movable longitudinally, said piece having means whereby the rods may be held in any desired position, substantially as described. 65

2. The combination with a frame, of a shutter, a rod pivoted thereto, a second rod pivotally connected to the first rod, a device pivotally supported on the window-sill through which said rods are movable longitudinally, and means on the window-sill independent of the said device and placed to engage one of the rods when the shutter is in its open position, thereby preventing motion of the same, substantially as described. 75

3. The combination with a window-frame, of a shutter pivotally-connected rods pivoted thereto, a pivotal piece within the frame through which the rods are movable longitudinally, and a notched piece on the outer portion of the window-sill placed to engage the rods when they are in a position to retain the shutter in its open position, substantially as described. 80

4. In a shutter-operating device, the combination with a frame, a sash, and a shutter, of pivotally-connected rods pivoted to the shutter, a substantially cylindrical piece movable on a vertical axis having an opening for the passage of said rods, said piece being held 90 in the square and bead of the frame, and provided with an inclined clamping-screw whereby said rods may be retained in any desired position, substantially as described. 85

5. In a shutter-operating device the combination with a frame, a sash and a shutter, of pivotally-connected rods pivoted to the shutter, a piece set in the square and bead of the frame and provided with a socket, a pivotal piece revolvably placed therein and constructed to receive said rods, and means for retaining said rods in any desired position, substantially as described. 95

In testimony whereof I have signed my name to this specification in the presence of 105 two subscribing witnesses.

JOSEPH F. STACKHOUSE.
